UNITED STATES PATENT OFFICE.

WILLIAM FRANCIS MULLANEY AND JAMES JOSEPH MULLANEY, OF BUFFALO, NEW YORK.

HAYRACK.

1,359,824.

Specification of Letters Patent. Patented Nov. 23, 1920.

Application filed January 7, 1919. Serial No. 269,985.

To all whom it may concern:

Be it known that we, WILLIAM FRANCIS MULLANEY and JAMES JOSEPH MULLANEY, citizens of the United States, residing at 5 Buffalo, in the county of Erie and State of New York, have invented certain new and useful Improvements in Hayracks; and we do hereby declare the following to be a full, clear, and exact description of the same, such 10 as will enable others skilled in the art to which it appertains to make and use the same, reference being had to the accompanying drawings, and to figures of reference marked thereon, which form part of this 15 specification.

Like figures of reference refer to like parts.

This invention relates to hay racks, particularly that kind thereof having attachments to facilitate the loading and the unloading of the rack.

One of the objects of this invention is to provide means attachable to the ordinary hay rack, which any farmer can apply, that 20 will convert his rack into a very serviceable and complementary rig to his hay elevator.

A further object is to provide such convertible means as will be readily releasable, to facilitate the unloading of the hay by a 25 power fork.

Another object is to provide releasable and adjusting means for supporting and laterally positioning detachable side lattice walls for releasing the first half load laterally, when the farmer is about to move the 30 same forward to make space for the second half loading.

Another object is to provide with a traveler adapted for loading the rack in halves, 35 two means for securing the traveler to the body of the rack, one of said means being adapted to hold and also to move said traveler, and the other being adapted for holding the traveler vertically to the rack, yet 40 permitting of a longitudinal movement of the said attachment, as well as the easy removal of the same, when the rack is to be used for other purposes.

With these and other objects, our invention resides in certain construction, one embodiment of which is shown in the drawings and is hereinafter described and what we claim is set forth hereinafter.

In the drawings, 50 Figure 1 is a perspective view of a hay

rack having attachments embodying our invention, and showing the parts in position to receive the first part of the load from the elevator.

Fig. 2 is a side elevation of the device 60 shown in Fig. 1, having the parts in position, including the first half of the load drawn forward leaving the rack ready to receive the last half of the load from the elevator; which is preferably placed to the 65 rear of the wagon for loading.

Fig. 3 is a front elevation of the rack and attachments shown in the other figures.

Fig. 4 is a perspective view of parts of the traveler, showing the interlocking track construction with the rollers, using channel irons.

Fig. 5 is a perspective view of one of the rack cross arms, and a stake of one of the side lattice walls, showing the releasable and 75 adjusting features of the supporting means.

In the figures, the body of the rack is shown to have the usual two beams 1 and 2, connected below by cross pieces 3, 3, 3, 3, and above by cross arms 4, 4, 4, 4, and connecting 80 the outer ends of the cross arms 4, 4, 4, 4, on each side are the stringers 5, 5. Symmetrically spaced about the center of the rack body, above the beams 1 and 2 are the parallel inturned channel irons 6 and 7, resting 85 upon the cross arms 4, 4, 4, 4, and secured thereto by the angle pieces 8, 8, 8. Fixed to the two rear cross arms 4, 4, are short boards 9, 9, 9, longitudinally positioned and spaced with reference to the channel irons 90 6 and 7, and the stringers 5, 5; those boards between the irons 6 and 7, being positioned to permit the traveler A to pass over them freely.

The traveler A is made as follows: Upon two stringer channel irons 10 and 11, are fixed 95 cross boards 12, 12, 12. Two roller shafts 13 and 14 are journaled in the channels 10 and 11, and in reinforcing patches 15, 15, thereon. The shafts 13 and 14 terminate in rollers 16, 16, 16, 16, which extend in between the flanges of the respective channel irons 6 and 7, to roll thereon. The rollers 16, 16, are of a diameter to turn freely between the flanges of the channels 10 and 11. At the forward end of the channels 10 and 100 11 is a front lattice 17, fixed thereto by means of bent angle irons 18, 18, also fixed to the stakes 19, 19.

In the front end of the rack body is journaled a windlass 20, having a shaft 21 and 110

a winding drum 22, to which is attached at the point B, a rope 23, wound thereon. The rope 23 is attached to a depending post 24 on the traveler A, and is made continuous, passing over a pulley 25 journaled in the rear of the rack body, and over a guiding cross rod 26, about the center of the said body. The windlass shaft 21 is journaled in a bracket 27, and terminates in a ratchet wheel 28 fixed thereto. A pawl 29, adapted to hold in either direction, is journaled on a pin 30, fixed in the bracket 27. A removable crank 31 is provided.

Referring to the rear construction of the rack, a rear lattice wall 32, is removably fixed in stake sockets 33, 33. Side lattice walls 34 and 35, are provided each with angle rods 36 and 37, secured by U-bolts to the ends of the stakes 38 and 39. The horizontal ends of the rods 36 and 37 each engage eye-bolts 40 and 41. The eye-bolt 41 having a hand screw 42, provided for clamping the angle rod therein at the position desired.

In operation, having the parts assembled as illustrated in the figures, having the traveler A with its lattice wall 17 in position as shown in Fig. 1, and having the pawl 29 set to hold the same there, by means of the rope 23 the elevator (not shown) is started and the box formed by the lattice walls 17, 34, 35 and 32 is filled with hay. The side walls 34 and 35 are next moved from forced contact with the hay, by releasing the hand screws 42 and pulling the said side walls partly out, then tightening the hand screws again. The pawl 29 is next reversed and the windlass 20 is then turned by revolving the crank 31 counter-clock wise causing the rope 23 to wind on the right half of the drum 22 and to unwind on its left half, playing over the idler pulley 25, in the rear, and the rope 23 pulls on the post 24 to drag the traveler A into the forward position as shown in Fig. 2 and held there by virtue of the locking action of the pawl 29. During the forward movement of the traveler A with its load, the rollers 16, 16, 16, track upon the bottom flange of the channel irons 6 and 7. Having brought the first half load to the front end of the wagon and secured the same there, the space thus vacated in the rear is filled from the elevator, and the load is drawn to the barn.

In case the driveway within the barn is not directly under the fork track of the power fork, and the load has to be drawn at an angle with the vertical, then the side toward which the fork will naturally draw the parts of the load as it removes the same, should be removed before unloading.

In transit, to overcome any possibility of shifting, by jolt or otherwise, the traveler A, from its proper engagement with its track the channels 6 and 7 by virtue of their

flanges, engaging the rollers 16, positively lock the same thereon, yet being open at the ends, permit of drawing the said rollers out of engagement therewith, in removing the traveler A, entirely from the hay rack. The lattice walls in the rear of the rack are easily taken off so that the rack can then be used for other purposes, as well as being possible to be readily put together again when required for service as a complementary device to the hay elevator.

It will be readily observed that our improved construction lends itself as a means of improving an ordinary hay rack at small expense, to increase the efficiency of the said rack as a farming implement. We also save in cost of construction over a specially designed hay rack to suit the requirements of the added features for accomplishing the same purpose.

We do not wish to be confined to the one embodiment of our invention herein shown and described as modifications can be made therein without departing from the spirit and scope of the invention.

Hence we claim—

1. In a hay rack, the combination with a rack body, of supporting means fixed to the top of said body, a vertical rack wall projecting above one edge of said top, and a bracket fixed to said rack wall and projecting transversely to the axis of said body and adjustably fixed to said supporting means, whereby said wall is releasably positioned transverse to said rack body while maintaining an upright position.

2. The combination in a hay rack with a rack body having a traveling hay carrier adapted for longitudinal reciprocation thereon, of side walls adjustably attached to said body for increasing the space therebetween to release a load of hay to be carried forward by said carrier, and means connecting said side walls with said body for positioning said walls transversely to said body while maintaining their upright position.

3. In a hay rack, the combination with a rack body, of a hollow bracket member fixed at the top part of said body, an upstanding wall positioned above the edge of said top part, a sliding member fixed to said wall and in sliding engagement within said hollow member, and clamping means adapted to releasably fix said sliding member within said hollow member and thereby adjusting said upstanding wall transversely to said rack body while maintaining its upright position.

4. In a hay rack, the combination with a rack body, of two eye bolts fixed at the top part of said body, an upstanding wall positioned above the edge of said top part, a rigid L-bar having a vertical leg fixed upon the lower part of said wall and having a horizontal leg slidably engaging the eyes of

said bolts and clamping means for releasably holding said L-bar whereby said upstanding wall is adapted to be adjustably positioned horizontally of said rack body.

5. In a hay rack, the combination with a rack body, of a longitudinal track upon the top of said body, a traveling hay carrier in engagement with said track, a pair of upstanding walls positioned on opposite sides 10 of said body, means connecting said wall with said body for adjustably positioning said walls horizontally of said body, whereby a load of hay can be released to be carried forward by said carrier, and other means 15 adapted to move said carrier upon said track.

6. The combination with a rack body, of a pair of tracks fixed thereon, said tracks comprising two parallel channels positioned

to have their flanges turned toward the center of said body, a carrier positioned above 20 said tracks, a pair of beam members fixed to the bottom of said carrier and spaced in the same plane with said channels, to be positioned having a beam member next to a 25 channel and between said channels, a plurality of parallel shafts journaled in and transverse to said beams and extending outside the same, two rollers, one fixed to each end of each of said shafts outside said beams and engaging the lower flanges of 30 said channel in rolling engagement therewith and held against lifting by the upper of said flanges.

Buffalo, N. Y., January 3, 1919.

WILLIAM FRANCIS MULLANEY.

JAMES JOSEPH MULLANEY.
